METHOD OF WELDING ENDS OF WIRE
FABRIC AND THE FABRICKarl Ulrich Schuster, Giengen-on-the-Brenz,
Germany, assignor to F. Oberdorfer G. m. b. H.,

In Germany March 15, 1929

17 Claims. (Cl. 140—3)

My invention relates to a method of connecting the ends of wire fabric.

It is an object of my invention to obtain a connection or seam at the ends which is without the drawback of seams as made heretofore.

To this end I connect the ends of the fabric by welding in such manner that the welding seam extends in parallel to, but substantially out of contact with the adjoining weft threads of the fabric.

It is desirable that the seams by which the ends of welding fabric are connected, for instance in screens of metallic cloths for paper-manufacturing machines, should be as strong and yielding and should move as smoothly on the cylinders, as the solid material. Another condition is that the permeability of the seam should be substantially equal to that of the solid material as otherwise the position of the seam will be marked on the paper.

It is rather difficult to obtain a seam which complies with these conditions, and seams as made heretofore are not satisfactory. As a rule the ends of the fabric are connected by sewing with wire, the sewing wire engaging weft threads which are secured to the warp threads by special means. Such a seam while possessing the desired properties as to strength and yielding has the drawback that it is thick and that the sewing wire partly clogs the meshes of the fabric. In seams of other types the metal required for connecting the ends of the fabric also increases the thickness of the fabric at the seam.

These drawbacks are eliminated according to my invention. In addition my method is performed by simple means and at high speed, and the seams obtained are very uniform.

In the drawings affixed to this specification and forming part thereof apparatus for performing my method, various modifications of my method, and the seams obtained, are illustrated diagrammatically by way of example.

In the drawings

Fig. 1 is an elevation of a welding apparatus,

Fig. 2 illustrates, on a larger scale, a method in which the warp threads in the ends of the fabric are staggered,

Fig. 3 illustrates the seam obtained,

Figs. 4 and 5 illustrate two methods in which the warp threads are aligned, and

Fig. 6 illustrates a fabric obtained by either of the methods illustrated in Figs. 4 and 5.

Referring now to the drawings, and first to Fig. 1, *m* is a base plate, *g* and *h* are links which are pivoted on said base plate at *i* and *k*, respec-

tively, *c* and *d* are supports for the ends of the fabric which are pivoted to the links *g* and *h* at *e* and *f*, respectively, means such as wing nuts being provided for clamping the joints at *i*, *k* and *e*, *f*, respectively, *n* and *o* are plates for holding the ends of the fabric on the supports *c* and *d*, respectively, and *p* is a welding burner which is arranged at the level of the point where the supports *c* and *d* are abutted. The apparatus is made adjustable for arranging the ends of the fabric at the most suitable angle for the welding operation.

Referring now to Figs. 2 and 3, *a* and *b* are the ends of a fabric, or of two fabrics, which are to be connected by welding. As will appear from Fig. 3, the ends of the fabric or fabrics are so placed with respect to each other that the warp threads *r* in the fabric *a* are staggered with respect to the warp threads *s* in the fabric *b*. As shown in Fig. 2 the ends *a* and *b* are placed between the supports *c*, *d* and the plates *n*, *o* so that the ends of the warp threads overlap each other. If necessary, one of the weft threads *t*, *u* is removed. Preferably the ends *a*, *b* are so arranged with respect to each other that the pitch of the weft threads *t*, *u* in the vicinity of the seam *v* is equal, or substantially equal, to the pitch of the weft threads in the solid material. The edges of the plates *n* and *o* which are preferably beveled, are placed so as to conceal the ends *a*, *b*, with the exception of the free ends of the warp threads *r*, *s*. The sides of the warp threads are in contact and when heated by the burner *p*, they are melted down and welded together.

The welding operation may be performed in various ways, for instance, a plurality of burners *p* may be distributed all over the width of the fabric or, which is more simple, a single burner, or group of burners is gradually moved along the seam. I am not limited to a burner as the welding element but may perform the welding operation by any other, for instance electrical, means.

The seam *v* which is obtained in this manner is substantially equal to a weft thread as to position, size, and function and therefore the seam is substantially equal to the solid material of the fabric as to strength, resiliency and action on the paper pulp.

The welding of the seam *v* as described requires a certain skill for obtaining uniformity of the fabric at the seam. The welding operation is easier if the warp threads are not arranged in staggered or overlapping relation but are aligned as shown in Fig. 6. In this case the warp threads are only connected with the threads

which are aligned, but not with the threads which are parallel to them so that the transverse web or bar constituted by the seam *v* in Fig. 3 is eliminated and the wires *r* and *s* extend across the seam *w-w* in the normal position, Fig. 6. This method apart from its requiring less skill than the method in which the warp threads are staggered, has the further advantage that the ends of the warp threads which project from the fabric are shorter so that the pitch of the weft threads at either side of the seam is made exactly, and not only substantially, equal to the pitch in the solid fabric without difficulty.

Referring now to Fig. 4 the ends of the aligning warp threads *r* and *s* are so arranged that while the end of the thread *s* in the fabric *b* abuts against the curved concave end of the thread *r* in the fabric *a*, the end of the thread *r* overlaps the end of the thread *s*. Otherwise the method is performed as described.

It may also be performed as illustrated in Fig. 5, with the ends of the wires *r* and *s* abutting. In both cases the pitch of the weft threads *t*, *u* at the ends is equal to that of the threads in the solid fabric.

As will appear from Fig. 6, a fabric the ends of which are connected in the manner illustrated in Fig. 4 or Fig. 5 is uniform throughout.

It is possible to thicken the several welds at the warp threads but in this case the thickened parts should be on the side of the fabric which is up, that is, on the side which is not in contact with the cylinder or any other part. Besides, the thickened parts should be staggered with respect to the weft threads *t* and *u*.

In this method as well as in the methods described, the welding operation may be performed as desired, with or without welding powder, solder, and the like.

Various changes may be made in the details disclosed in the foregoing specification without departing from the invention or sacrificing the advantages thereof.

In the claims affixed to this specification no selection of any particular modification of the invention is intended to the exclusion of other modifications thereof and the right to subsequently make claim to any modification not covered by these claims is expressly reserved.

I claim:—

1. The method of welding wire fabric which comprises trimming the two extremities of fabric to be united by cutting them substantially along a line of the endmost weft thread, placing said extremities in position to bring the free end of each warp thread of one extremity in contact with the free end of a warp thread of the other extremity the length of such contacts being approximately equal to the thickness of a weft thread and joining the so contacting ends by welding, whereby the line of weld takes the place of a weft thread and simulates the same.

2. The method of welding wire fabric which comprises trimming the two extremities of fabric to be united by cutting them substantially along a line of the endmost weft thread, placing said extremities in position to bring the free end of each warp thread of one extremity in contact with the free ends of two warp threads of the other extremity, and joining the so contacting ends by welding.

3. The method of welding wire fabric which comprises trimming the two extremities of fabric to be united by cutting them substantially along

a line of the endmost weft thread, placing said extremities in position to bring the free end of each warp thread of one extremity in contact with the free end of a warp thread of the other extremity, and joining the so contacting ends by welding.

4. The method of welding wire fabric which comprises trimming the two extremities of fabric to be united by cutting them substantially along a line of the endmost weft thread, placing said extremities in position to bring the free end of each warp thread of one extremity in contact and in line with the free end of a warp thread of the other extremity, and joining the so contacting ends by butt welding.

5. The method of welding wire fabric which comprises trimming the two extremities of fabric to be united by cutting them substantially along a line of the endmost weft thread, placing said extremities in position at an angle to one another to bring the free end of each warp thread of one extremity in contact with the free end of a warp thread of the other extremity the length of such contacts being approximately equal to the thickness of a weft thread and joining the so contacting ends by welding, whereby the line of weld takes the place of a weft thread and simulates the same.

6. The method of welding wire fabric comprising placing the extremities to be united in position at an angle to one another with the free end of each warp thread of one extremity in alignment with the free end of a warp thread of the other extremity and connecting each warp thread of one extremity to a warp thread of the other extremity by welding said ends together at a point between two consecutive weft threads; the axes of the individual warp threads of the two extremities lying in a common plane at the time of welding.

7. The method of connecting two extremities of wire fabric comprising arranging free ends of the warp threads of one extremity in alignment with free ends of the warp threads of the other extremity, the ends of the aligned wires substantially contacting with one another, and uniting the said contacting ends of said wires by welding out of contact with the weft threads of said extremities.

8. The method of connecting two extremities of wire fabric comprising arranging each of the axes of the warp threads of one extremity in common planes, extending at right angles to the planes of the said extremities, with each of the axes of the warp threads of the other extremity, the ends of the so-aligned wires substantially contacting with one another, and uniting the said contacting ends of said wires by welding.

9. A wire fabric comprising two extremities welded together by a welding seam parallel to the weft threads, the warp threads of one extremity being united individually with and directly to the warp threads of the second extremity by welded joints within the space between two adjacent weft threads and out of contact with said weft threads.

10. The wire fabric of claim 9 wherein the individual warp threads of the two extremities of fabric are in line.

11. The wire fabric of claim 9 wherein the individual warp threads of the two extremities of fabric are in staggered relationship.

12. In the uniting of pieces of wire fabric by

- welding, the process which comprises placing two pieces of wire fabric end to end, the said two pieces being at an angle of less than 180° with each other and the said ends having warp wires 5 projecting beyond the end weft wires, and uniting the ends of said projecting warp wires of said two pieces in pairs by welding within the space between the said end weft wires and out of contact with the said weft threads.
- 10 13. The process of claim 12 wherein the axes of each pair of warp wires which are united by the welding of said two pieces of fabric lie within a common plane at right angles to the planes of the said pieces of fabric.
- 15 14. The process of claim 12 wherein the ends of the warp wires of said two pieces of fabric are placed in end to end abutment prior to welding.
15. A wire fabric with a transverse joint comprising a welding seam intermediate between and out of contact with the weft threads of said fabric.
16. A wire fabric consisting of two extremities of wire fabric united by welding and comprising welded joints, uniting the free ends of the aligned warp threads of said extremities and out of contact with any weft thread.
17. A wire fabric consisting of two extremities of wire fabric united by welding and comprising lap welded joints, uniting the free ends of the aligned warp threads of said two extremities and out of contact with any weft thread.
